Plastic Innovations, Inc., New York, N. Y., a
corporation of New York

Application January 11, 1951, Serial No. 13,759

Term of patent 7 years

(Cl. D34—15)

To all whom it may concern:

Be it known that I, Alexander Burkes, a citizen of the United States of America, residing at the city, county, and State of New York, have invented a new, original, and ornamental Design for an Inflatable Toy Animal Figure or Similar Article, of which the following is a specification, reference being had to the accompanying drawing, forming part thereof.

In the drawing:

Fig. 1 is a side view of an inflatable toy animal figure or similar article, showing my new design;

Fig. 2 is a top plan view thereof;

Fig. 3 is a front view thereof; and

Fig. 4 is a rear view thereof.

The essential features of my design reside in the portion shown in full lines.

I claim:

The ornamental design for an inflatable toy animal figure or similar article, substantially as shown and described.

ALEXANDER BURKES.
